CLAIM

The ornamental design for a roof assembly for automobile, as shown and described.

DESCRIPTION

FIG. 1 is a front elevational view of a roof assembly for automobile showing our new design;

FIG. 2 is a left side view thereof;

FIG. 3 is a right side view thereof;

FIG. 4 is a top plan view thereof;

FIG. 5 is a bottom plan view thereof; and,

FIG. 6 is a front, top and right side perspective view thereof.

The broken lines in the drawings illustrate portions of the roof assembly for automobile which form no part of the claimed design.
